CASSETTE FEEDING APPARATUS

Darrell S. Staley, Santa Clara, Calif., assignor to Ampex Corporation, Redwood City, Calif.

Filed Apr. 1, 1970, Ser. No. 22,148

Term of patent 14 years

Int. Cl. D14—02

U.S. Cl. D26—5

The figure is a perspective view of the front, top and left side of a cassette feeding apparatus showing my new design, the back and bottom being conventionally plain, and the end panels on the right side being identical to the lower end panel on the left side.

I claim:

The ornamental design for a cassette feeding apparatus, substantially as shown and described.
